UNITED STATES PATENT OFFICE.

WILLIAM F. DRAPER, OF HOPEDALE, MASSACHUSETTS.

PROTECTION MECHANISM FOR LOOMS.

No. 911,219.

Specification of Letters Patent.

Patented Feb. 2, 1909.

Application filed December 14, 1908. Serial No. 467,521.

To all whom it may concern:

Be it known that I, WILLIAM F. DRAPER, a citizen of the United States, residing at Hopedale, in the county of Worcester and

5 State of Massachusetts, have invented an Improvement in Protection Mechanism for Looms, of which the following description, in connection with the accompanying drawings, is a specification, like figures on the 10 drawings representing like parts.

The invention to be hereinafter described relates to protection mechanism for looms, the general function of which is to stop the 15 loom when a shuttle fails to be or is improperly boxed.

In such mechanism as heretofore employed the dagger has been given a movement of more or less amplitude towards and from operative position on each cycle of lay 20 action, and especially has this been the case with protection mechanism operating in conjunction with a shuttle binder with consequent objections well understood by those skilled in the art.

25 With the above general facts in view the aims and purposes of the present invention will best be made clear by the following description and accompanying drawings of one form of means for putting the same into 30 practical effect, the true scope of the invention being definitely pointed out by the claims.

In the drawings:—Figure 1 is a side elevation of sufficient portions of a loom having 35 associated therewith the features of the present invention to make clear the relation and operation of parts, the lay and shuttle-box being shown in section; Fig. 2 is a top plan view of one end of the lay and its shuttle- 40 box and some of the adjacent devices, the shuttle being shown properly boxed; Fig. 3 is a section on the line 3—3, Fig. 2; and Fig. 4 is a detached detail view, partly in section, showing one form of guide for the dagger controller.

45 Referring more particularly to Figs. 1 and 2, the lay 1, the front box-plate 2, the cover plate 3, and the back wall 4 of the shuttle box, the shipper 5, the knock-off lever 6, and 50 the main portion of the frog 7 may be of well-known or other desired character. A shuttle binder 8 pivotally and adjustably mounted, as at 9, is provided with a shoe 10, preferably

formed of metal, said shoe being movable by or with the binder over the top of a guide 55 11, secured to the back portion of the lay as will more fully appear hereinafter.

Supported to bear upon the binder 8 is a spring 12, preferably supported by a bracket 13 through the medium of an adjusting screw 60 or like device 14, the construction being such that adjustment of the screw 14 will vary the tension of spring action on the binder 8, as will be readily understood.

Mounted in suitable supports carried by 65 the lay 1 is the dagger rod 15, carrying a dagger 16, the nose 17 of which is adapted to engage the shoulder 18 of the frog 7 and move said frog when said dagger is permitted to drop on the forward movement of 70 the lay, as usual. A spring 19, Fig. 2, normally tends to turn the dagger rod 15 to cause the dagger to assume its dropped or frog engaging position.

Extending from the dagger rod 15 is the 75 arm 20, which, with the rod 21 pivotally connected thereto, constitutes one form of controller for controlling the position of the dagger as determined by the binder 8, as 80 will presently appear. The controller rod 21 extends upward from the arm 20 into the guide 11, said guide 11 being so formed as to permit movement of the end of rod 21 in a direction corresponding to the general direction of binder movement, as the latter turns 85 about its pivotal connection 9. To this general end the guide 11 is provided with an elongated slot 22, Figs. 2 and 4, preferably open at its outer end, as shown, though this is not essential, and the controller rod 21 has 90 a spring 23 acting thereon and tending to maintain the end of the controller rod 21 in the part of the slot 22 nearest the shuttle box, as indicated in Fig. 3.

The frog 7 is provided with a riser 24 and a 95 dagger support 25, which co-operates at times with a shoe 27, Fig. 1, adjustably mounted on the dagger 16, by suitable means, as the bolt 28, said shoe 27 preferably extending, as at 29, to constitute a stop for limiting the 100 upward turning movement of the dagger by contacting with the bottom of the lay 1.

If it be assumed that the loom has been stopped by the protector mechanism and is to be again started, the shoe 27 will, on the 105 backward movement of the lay, ride up the

riser 24, lift the dagger, and lower the controller, so that when the shuttle enters the box the binder will be moved outward and the shoe 10 will move over the end of the controller rod 21, thus maintaining the dagger in raised or inoperative position as the lay moves forward to "beat up." As the lay again moves to the rear, the shoe 10 continues in position over the end of the controller rod 21 until the shuttle is picked, which takes place when the lay has carried the dagger to position the shoe 27 above the dwell or support 25 of the frog. Thus as the shuttle moves through the shed and the end 15 of the controller rod 21 is uncovered by the inward movement of the binder, the dagger is still held in its inoperative or raised position by the shoe 27 riding over the dwell or support 25, and when the shuttle passes into 20 the box on the other side of the loom, the shoe 10 of that binder moves over the end of the controller rod 21 at that end of the lay, and, as the lay moves forward, prevents the controller rod 21 on that end of the lay from 25 rising, thus the dagger continues to be held in its raised or inoperative position so long as the loom continues in normal working condition.

It is to be noted that the dagger is not 30 raised and lowered on each round of lay movement, as heretofore, but, under normal working conditions when the shuttle is properly boxed on each pick, the dagger remains in its raised or inoperative position, and is 35 only lowered or moved therefrom when a shuttle fails to be or is improperly boxed.

From the construction and operation of the loom and its protection mechanism as above outlined, it will be noted that more or 40 less wear is liable to occur between the lower surface of the shoe 10 on the binder and the top of the controller rod 21, but by providing the controller rod with capacity for motion with the binder, it will be evident that after 45 the end of the rod 21 is in contact with the shoe 10 and is sustaining the tension of the dagger rod spring 19, thereby holding the dagger in raised position, any outward movement of the shoe or binder will cause 50 the controller rod 21 to turn on its pivotal connection with the arm 20 and move with the shoe or binder, thus preventing any injurious wear or scoring of the parts as might result by sliding one on the other while 55 forcibly held in contact.

Should it be desired to move the binder by hand at any time, the construction is such that no material resistance is offered to such movement by the controller rod, because if 60 the controller rod be raised and in the path of the binder or its shoe said rod may yield to outward movement of the binder; or if said rod is, at the time, bearing against the under surface of the shoe or binder, it will move 65 about its pivotal connection with the arm 20,

as the binder is moved outward, thus avoiding wear such as might occur if the shoe were moved across the end of the controller.

What is claimed is:

1. In a loom, the combination of a lay, a shuttle box and its binder, protection mechanism including a dagger, a dagger controller, and means including the binder and dagger controller for holding the dagger in inoperative position during the cycle of lay movement, said dagger controller having a member movable with the binder without affecting the position of the dagger. 75

2. In a loom, the combination of a lay, a shuttle box and its binder, protection mechanism including a dagger, and a dagger controller having a member adapted to contact with the binder to hold the dagger in inoperative position when a shuttle is properly boxed, said member being movable with the binder 85 and permitting the dagger position to be unaltered by such movement. 80

3. In a loom, the combination of a lay, a shuttle box, protection mechanism including a dagger, means moved by the shuttle as it is properly boxed to prevent movement of the dagger to operative position, and a member connected to the dagger and movable with said means while permitting the dagger position to remain unaffected by said movement. 90

4. In a loom, the combination of a lay, a shuttle box at each end of the lay, binders for said shuttle boxes, protection mechanism including a dagger, and a dagger controller having a member movable in a direction crossing the plane of movement of a binder as the dagger moves to operative position, said binder preventing such movement of the dagger when the shuttle is properly boxed, 105 and said member being movable with a binder without changing the position of the dagger. 100

5. In a loom, the combination of a lay and shuttle boxes, protection mechanism including a dagger, means normally tending to move the dagger to operative position, a dagger controller, and a shuttle binder movable over the end of the controller as a shuttle is properly boxed to prevent movement of the dagger to operative position, 110 said controller being movable with the binder 115 without changing the position of the dagger.

6. In a loom, the combination of a lay and shuttle boxes, protection mechanism, and means including a part on a shuttle box and a part connected to the protection mechanism to prevent operative positioning of said mechanism when a shuttle is properly boxed, said part connected to the protection mechanism being movable with the part on the shuttle box without affecting the position of the protection mechanism. 120

7. In a loom, a lay, a shuttle box at each end thereof, binders for said shuttle boxes, 125

and protection mechanism including a dagger, a dagger controller, a guide on the lay for said dagger controller directing the same to move into contact with a binder when

5 said binder is moved outward from the shuttle box, and permitting said dagger controller to move with the binder after said contact is established.

8. In a loom, the combination of a lay, a 10 shuttle box, a binder therefor, protection mechanism including a dagger, a dagger controller including a rod, and a slotted guide on the lay for guiding said rod into contact with the binder to thereby prevent movement of the dagger to operative position and permitting said rod to move with the binder.

9. In a loom, the combination of a lay, a 15 shuttle box, a slotted guide, a shuttle binder

movable over said slotted guide, and protection mechanism, including a rod movable in said guide towards the binder and movable in said guide with the binder.

10. In a loom, the combination of a lay, a 20 shuttle box, a slotted guide, a shuttle binder movable over said slotted guide, and protection mechanism, including a spring actuated rod movable in said guide towards the binder and movable in said guide with the binder.

30 In testimony whereof, I have signed my name to this specification, in the presence of two subscribing witnesses.
